Atty's

UNITED STATES PATENT OFFICE.

FLORENCE I. HAMMOND, OF CHICAGO, ILLINOIS.

ARTICLE OF JEWELRY.

Application filed August 11, 1923. Serial No. 656,859.

To all whom it may concern:

Be it known that I, FLORENCE I. HAMMOND, a citizen of the United States, residing at Chicago, in the county of Cook and 5 State of Illinois, have invented a certain new and useful Improvement in Articles of Jewelry, of which the following is a full, clear, concise, and exact description, reference being had to the accompanying drawings, forming a part of this specification.

My invention relates to an article of jewelry and while I shall illustrate and describe the invention in connection with embodiments appearing in the form of rings 15 and bracelets, it is to be understood that the invention is not to be limited to rings and bracelets but applies to articles of jewelry such as are worn upon the body or clothing. More specifically my invention 20 relates to the mounting of ornamental articles such as stones, beads and the like, upon an article of jewelry for the purpose of giving it a changeable and attractive appearance. So far as I am aware it is new 25 to have a cluster of stones, beads or other ornamental articles mounted upon an article of jewelry of this character for the purpose of free movement of such stones, beads and the like to permit them to be displayed 30 more freely and to give a light and dainty appearance to a group of ornaments which would otherwise appear heavy and uncouth.

According to my invention I mount a 35 plurality of pendant stones, beads or the like upon a ring, bracelet or other article of jewelry by means of links which permit free motion of such linked articles with respect to the ring, thereby giving the ring and its pendant ornaments a live and sparkling appearance which is highly desirable. I may if desired make the linkage so short 40 that the pendant stones, beads or the like, which I shall herein term pendants, shall not contact with the skin of the wearer or 45 the article of clothing upon which the device is mounted, and shall only contact with the mounting of the pendant on the article of jewelry. This may however be varied.

In order to acquaint those skilled in the 50 art with the manner of constructing and using my invention I shall now describe the same in connection with the accompanying drawings which illustrates an embodiment of the same.

In the drawings:

Figure 1 is a front elevational view of a ring embodying my invention.

Fig. 2 is an isometric view of the same.

Fig. 3 is a cross sectional view taken on line 3—3 of Fig. 1.

Fig. 4 is a cross sectional view of one of the pendants.

Fig. 5 is a fragmentary elevational view of a ring and escutcheon plate with a plurality of eyes for mounting the pendants.

Fig. 6 is a front elevational view of a modified form of ring embodying the invention.

Fig. 7 is an isometric view of a bracelet embodying the invention.

Fig. 8 is a cross sectional view taken on the line 8—8 of Fig. 7, and;

Fig. 9 is a fragmentary view of a modified form of mounting the pendant in the case of precious or semiprecious stones.

As indicated in Fig. 1, the band or body 1 of the ring is split and the ends are brought under the escutcheon plate 2 which is mounted centrally upon the ring, being secured thereto in any suitable manner. The band of the ring is thus split merely for convenience and not of necessity, to adapt the same band to different sizes. If desired, and as shown in Fig. 6, a solid band may be employed. The escutcheon plate 2 has formed thereon the eyes 3 which in the present case are illustrated as being punched up out of the stock of plate 2. This manner of forming the eyes is inexpensive and convenient but the eyes may be formed by attaching separate pieces of metal to the face of the plate 2 or in any other well known manner. A series of small links 4 are passed through the eyes 3 and are linked with each other to form a loose and flexible mounting for the pendant members 5 which have shanks 6 formed thereon as illustrated in Fig. 4.

These pendants 5 may be made of metallic beads, glass or other beads, precious or semi precious stones or any combination of the same. The particular material of which the pendants 5 are constructed and their particular appearance is not of the essence of the present invention. However, it is highly desirable that these beads or pendants be of an attractive appearance and that they be of such character that they give a more or less sparkling and lively appearance as they

move about. It is highly desirable that these pendants be as fluent in their motion as possible, to enhance the appearance of the ring. Obviously, such freedom and facility of motion gives them a live and attractive appearance. However, movement of the pendants may be confined to some extent by the mounting. Furthermore, the limiting of the motion of the pendants by the mounting is desirable in that it preserves the proper color scheme and symmetry which might otherwise be defeated, by too great an extent of travel of the pendant. It is not necessary that the intermediate links 4 be all linked to each other nor in fact that they be common to a plurality of pendants, but I have found such construction to be advantageous and desirable.

Any desired number of mounting eyes on the escutcheon plate 2 may be provided. I have found that mounting these pendants from a plurality of points is more desirable than connecting them all to a common central point because it permits of greater freedom of motion.

In Fig. 5 I have shown four of the eyes on escutcheon plate 2 for mounting the pendants. In Figure 6 I have shown merely a central eye 7 to which are connected the intermediate links 8—8. The pendants 5—5, only two of which are shown in Figure 6, have their shanks 6 connected through the links 8 with the central eye 7. It will be observed in Fig. 6 that the links 8 and pendants 5 when extended permit the pendant to contact with the outer rim of the mounting 9 which is merely an integral enlargement of the band 10 of the ring.

I have shown in Fig. 7 a bracelet 11 embodying the invention. The bracelet comprises a split band 12 which in this case is formed of relatively thin metal having integral eyes 13 struck up therefrom as in the case of the escutcheon plate of the ring above referred to. Obviously these eyes may be formed in any other manner as will be apparent to those skilled in the art. To these eyes 13 there are connected clusters 14 of pendants such as the pendant 5 above described and illustrated. The pendants are connected to the eyes 13 through the intermediary of suitable links 15 which may be individually connected to the eyes and to the pendants or they may be linked together and to the eyes and to the pendants. The linkage connection in this case also, is designed to permit great freedom or fluidity of motion of the pendant so as to give them the desired effect.

I do not intend the invention to be limited to bracelets and rings or such articles as are worn directly upon the skin of the user, but also to such other articles of jewelry as are mounted upon the clothing or person of the

user. I am aware that beaded fringes and the like are old in the art, but my invention has nothing in common with them.

I do not intend to be confined to the details shown or described. The pendants 5 are preferably of a material or color which 70 contrasts sharply with the mounting.

In Fig. 4 I have illustrated one form of connecting the bead of the pendant with the eye 6. Obviously this may be varied. Where precious or semi precious stones are 75 employed the stone or bead 5' may be grasped in prongs 16 lying outside of the stone or bead as is common in mounting such stones in a stationary mounting.

The loose mounting of the pendants permits the same to lie flat so that a glove may be drawn upon the hand without serious interference.

I claim:

1. An article of jewelry comprising a band adapted to embrace a portion of the body of the wearer, a mounting plate mounted on said band, said mounting plate having a plurality of eyes formed thereon, and a plurality of pendants freely linked to said eyes.

2. An article of jewelry comprising a band adapted to embrace a portion of the body of the wearer, said band having a polygonal plate mounted thereon, a plurality of eyes punched out of the stock of said plate, said eyes projecting outwardly from and substantially perpendicular to the plate, and a plurality of pendants freely linked to said eyes and capable of having motion in all directions, but limited by each other and by said polygonal plate.

3. An article of jewelry comprising a band adapted to embrace a portion of the body of the wearer, a polygonal plate mounted on said band, a plurality of eyes punched out of said plate, a series of links passing through said eyes and linked with each other to form a flexible mounting, and a plurality of pendants loosely mounted on 110 said flexible mounting.

4. An article of jewelry comprising a band adapted to embrace a portion of the body of the wearer, said band having a hexagonal plate mounted thereon, said plate having four eyes punched out of its stock so as to project outwardly and substantially perpendicular thereto, the top portions of said eyes being relatively flat and the openings therein being relatively rectangular in form, a plurality of links passing through the relatively rectangular openings in said eyes so as to form a flexible mounting, and a plurality of pendants loosely mounted on said flexible mounting.

In witness whereof, I hereunto subscribe my name this 8 day of August, 1923.

FLORENCE I. HAMMOND.
